Primary Examiner — Mojtaba Tehrani(57) **CLAIM**

The ornamental design for a magazine loader, as shown and described.

DESCRIPTION

FIG. 1 is a perspective view of a magazine loader showing my new design;
 FIG. 2 is another perspective view thereof;
 FIG. 3 is another perspective view thereof;
 FIG. 4 is a front elevational view thereof;
 FIG. 5 is a rear elevational view thereof;
 FIG. 6 is a left side elevational view thereof;
 FIG. 7 is a right side elevational view thereof;
 FIG. 8 is a top plan view thereof;
 FIG. 9 is a bottom plan view thereof; and,
 FIG. 10 is a perspective view of the magazine loader where the magazine loader is in a configuration of use.
 The broken lines in the drawings depict portions of the magazine loader that form no part of the claimed design.
